CLAIM

The ornamental design for a reflective tape for ornamenting a garment, as shown and described.

DESCRIPTION

FIG. 1 is a front view of a reflective tape for ornamenting a garment according to the present invention.

FIG. 2 is a left side view thereof.

FIG. 3 is a right side view thereof.

FIG. 4 is a bottom view thereof.

FIG. 5 is a top view thereof; and,

FIG. 6 is a front view of the reflective tape for ornamenting a garment of FIG. 1 shown in a position of use with environmental subject matter.

The broken lines in FIG. 6 depict environmental subject matter that forms no part of the claimed design.

1 Claim, 4 Drawing Sheets
